UNITED STATES PATENT OFFICE.

GEORGE A. WHITE, OF BOSTON, MASSACHUSETTS.

KNITTING-MACHINE.

SPECIFICATION forming part of Letters Patent No. 336,611, dated February 23, 1886.

Application filed December 22, 1884. Serial No. 150,958. (No model.)

To all whom it may concern:

Be it known that I, GEORGE A. WHITE, of Boston, in the county of Suffolk and State of Massachusetts, have invented certain Improvements in Knitting-Machines, of which the following is a specification.

This invention relates to circular-knitting machines equipped with reciprocating needles; and it consists in the improvements herein-
10 after described and claimed.

Of the accompanying drawings, forming a part of this specification, Figure 1 represents a side elevation and partial section of an entire machine embodying my improvements. Fig. 15 2 represents a top view of the upper portion of the same. Fig. 3 represents a section on line xx , Fig. 2. Fig. 4 represents a perspective view of the machine, excepting the mechanism whereby the upper needle-cylinder is 20 prevented from rotating. Fig. 5 represents a vertical section of the machine as represented in Fig. 4. Fig. 5^a represents a section of the ring b^a . Fig. 6 represents a side elevation of the lever, (shown edgewise in Fig. 5,) and a 25 section of the part co-operating therewith. Fig. 7 represents a perspective view of portions of the machine, showing the latch-openers and fenders whereby the needle-latches are controlled. Fig. 8 represents a side elevation and partial section of the parts shown in Fig. 30 7. Figs. 9 and 10 represent inside views of the feeds, latch-openers, and fenders. Fig. 11 represents a transverse vertical section of the upper cam-cylinder, showing the needle-path arranged for action. Fig. 12 represents a section on line yy , Fig. 11. Fig. 13 represents a transverse vertical section of the upper needle-cylinder, showing the needle-path arranged to hold the upper needles motionless. 35 40 Fig. 14 represents a portion of the lower cam-cylinder developed on a flat surface. Fig. 15 represents a side view of the upper needle-cylinder. Fig. 16 represents a side view of the lower needle-cylinder. Fig. 17 represents 45 a perspective view and partial section of the base of the machine inverted.

The same letters of reference indicate the same parts in all the figures.

In the drawings, a represents the fixed supporting-base, to which is rigidly attached the lower needle-cylinder, b , having vertical slots

in which are placed the usual hooked and latched needles, c .

d represents the inclosing shell or casing of the lower cam-cylinder, e , which has the needle-path for the lower needles. The casing d is fitted to rotate on the base a , and is provided with a bevel-gear, f , meshing with a bevel-gear, g , on the operating-shaft h .

i represents the upper cam-cylinder, having 60 the needle-path for the inverted upper needles, c^a , which co-operate with the lower needles, c , when the machine is used for producing ribbed work. The upper cam-cylinder and needle-cylinder may be called a "rubber attachment."

j represents the upper needle-cylinder, having slots for the upper needles, said cylinder being the frustum of an open or tubular cone, placed with its larger end downward, so that the upper needles are inclined, as shown 70 in Fig. 4.

The upper needle-cylinder is contained in and supported by the upper cam-cylinder, i , an outwardly-projecting flange, k , secured to the upper end of the needle-cylinder, resting 75 on the upper edge of the cam-cylinder. A standard, l , rigidly attached to the upper cam-cylinder at its upper end, and having dovetail sides at its lower end, inserted removably in a dovetail socket in a projection, m , on the shell d , supports the upper cam-cylinder and causes it to rotate with the shell and with the lower cam-cylinder. The upper needle-cylinder is prevented from rotating with the cam-cylinder i by means of a segmental bar, n , rigidly held by a standard, o , hereinafter described, over the needle-cylinder, a series of sliding bolts or detents, p , radially arranged on said segmental bar, and pins q , arranged in pairs on the upper end of the needle-cylinder. 85 The bolts or detents p project between the pins q , as shown in Fig. 2, and thus engage the needle-cylinder with the bar n . The detents p are successively withdrawn from the pins q to permit the passage of the thread 90 around the upper cam and needle cylinders by means of a cam-surface, r , at the outer edge of the slotted thread-carrying flange, s , on the cam-cylinder i , said cam striking pins t , projecting downwardly from the detents p , and 100 moving each detent outwardly before the thread-carrying eye u reaches it. After the

thread has passed each detent, a cam-groove, *v*, following the cam *r*, receives the pin of the displaced detent and moves it back between the pins *q q*, with which it engages before the 5 next pin is withdrawn.

In this machine the upper needle-cylinder is held stationary while the upper cam-cylinder rotates. Heretofore in this class of machines the upper needle-cylinder has been 10 prevented from rotating with its cam-cylinder by feet projecting downwardly from the upper cylinder, and held by corresponding projections on the inner surface of the lower needle-cylinder, the knit fabric passing between the 15 feet on the upper cylinder and the projections on the lower cylinder, and being somewhat impeded by the grasping pressure it receives from said feet and projections.

The means employed by me, above described, 20 obviate any interference with the fabric, the upper needle-cylinder being entirely separate from the lower, and enable the upper needle-cylinder to be conveniently removed and applied. The standard *o*, supporting the segmental bar *n*, is swiveled at its lower end in a socket, *w*, attached to the base *a*, so that it can be turned to remove the segmental bar from its operative position and allow the upper cam and needle cylinders to be removed. The 25 standard *o* is secured to the socket *w*, when the segmental bar *n* is in place by a locking-lever, *a'*, pivoted to the socket and pressed by a spring, so that a catch in its upper end enters a socket in the standard, and also by tongues 30 *b' b'*, formed, respectively, on the standard and socket, each tongue entering a corresponding recess, as shown in Fig. 1.

A spiral spring, *c'*, is secured to the socket *w* at its lower end, and is engaged at its upper 40 end with pins *d' d'* on the standard *o*, the spring having a constant tendency to rotate the standard *o* in the direction indicated by the arrow in Fig. 2. When the lever *a'* is disengaged from the standard *o*, the spring *c'* first 45 raises the standard until the projections *b'* are disengaged from their recesses, and then acts on the pin *d'* to rotate the standard in the direction indicated, thus removing the segmental bar *n* from its operative position, the operator 50 having only to press inwardly on the lower end of the lever *a'* to effect this operation.

The standard *l*, that connects the upper and lower cam-cylinders, is provided with a lever, *e'*, pivoted at *f'* to the standard *l*, its lower end 55 bearing on the upper end of the socketed projection *m*. When it is desired to remove the standard *l* from the projection *m*, a side pressure against the lever will cause it to raise the standard sufficiently to loosen it and to enable 60 the operator to remove it.

An arm, *g'*, is pivoted at *h'* to an ear or lug, *i'*, on the lower cam-cylinder. To the upper end of said arm is attached a block, *j'*, projecting inwardly toward the needle-cylinder, 65 and having at its inner end a thin substantially triangular plate, *k'*, which stands close

to the outer surfaces of those lower needles which are held by the horizontal groove 3 of the lower cam-cylinder, hereinafter described. The plate *k'* constitutes an opener for 70 the latches of the lower needles, its upper edge, which is raised slightly at its ends, projecting into the center of the eye or hook of each needle and forcing outwardly any latches that fail to fall outwardly from the hooks by gravitation. A spiral spring, *l'*, placed under the pivot of the arm *g'*, forces said arm upwardly and holds it with the upper edge of the latch-opener projecting into the hooks of the lower needles, so that if the latch-opener were moved 75 outwardly from the needles it would strike the points of the hooks, it being therefore necessary to depress the arm *g'* before the latch-opener can be moved away from the needles. This projection of the latch-opener into the 80 hooks of the needles enables it to pass with certainty between the needles and such latches as remain raised when the latch-opener reaches them, said latches being thrown outwardly or opened by the opener, its position enabling it 85 to avoid striking and injuring the sides of the raised latches.

The arm *g'* is provided on its inner side with a shoe or fender, *m'*, which is located below the latch-opener *k'* and bears against the lower 90 needles through the hooks of which the latch-opener is passing. The office of this shoe or fender is to hold the needles firmly against the lower cylinder while the latch-opener is passing through their hooks, thus preventing 95 the possibility of injurious contact between the latch-opener and the needles. The shoe or fender *m'* is attached to a shank, *n'*, which is contained in a socket on the arm *g'*, and is adjusted in said socket by means of a screw, 100 *o'*, bearing against the rear end of the shank *n'*, said screw enabling the fender to be adjusted toward and from the needles for the purpose of adjusting the latch-opener laterally 105 in the eyes of the needles.

The arm *g'* is held in its operative position by a hook or catch, *p'*, attached to the ear *i'*, to which the arm is pivoted, said hook projecting through a slot in the arm *g'* and engaging with an elastic strip, *q'*, of steel attached to 110 the outer side of the arm and extending across the slot therein. The strip *q'* is slightly curved outwardly, so that it acts as a spring, bearing against the hook *p'* and pressing the arm *g'* inwardly, thus insuring a constant bearing of the 115 fender *m'* against the needles.

When the arm *g'* is to be turned on its pivot to separate the latch-opener and fender from the needles, it is first depressed against the upward pressure of the spiral spring *l'* until the 120 latch-opener is below the needle-hooks, and the strip *q'* is disengaged from the hook *p'* and is then turned outwardly, as shown in Fig. 8.

When the arm is being turned back to its operative position, the spiral spring yields 125 and allows the arm to be depressed by the contact of the strip *q'* with the hook *p'*, until the 130

strip passes under the hook, the spring t' then raising the arm and thus engaging the strip with the hook and inserting the latch-opener into the hooks of the needles.

5 The block j' , to which the latch-opener k' is attached, has a thread-guiding slot, r' , through which the thread passes directly to the lower needles when the rubber attachment is not used, and to the thread-guide, hereinafter described, depending from the upper cylinder when the rubber attachment is in use.

s' represents an arm pivoted to ears on the upper cam-cylinder, its lower end being pressed inwardly by a spring, t' . The lower 15 end of the arm s' is provided with a latch-opener, u' , for the latches of the upper needles. Said latch-opener is a diagonal finger formed on the inwardly-turned end of the arm s' , its lower end being reduced to a point which 20 stands in position to enter the centers of the closed eyes of the inverted upper needles and raise the latch thereof until they pass off from the upper end of the latch-opener, from which they drop onto the thread. The upper 25 end of the latch-opener u' is provided with a thread-guide or compound feed, v' , which delivers the thread to both sets of needles, the latches of the upper needles dropping from the upper end of the latch-opener u' falling 30 upon the thread passing from the feed v' and forcing it into the hooks of the upper needles, the falling movement of the latches being facilitated by the loops last formed, which surround the needles and exert a downward 35 pressure on the latches when they pass off from the latch-opener. Each upper needle after it has thus received the thread is drawn upwardly forming a new loop through the one previously formed.

40 w' represents an arm or guard projecting inwardly from the arm s' above the latch-opener u' . Said guard has an inclined edge, y' , which is substantially parallel with the inclined latch-opener u' , and is located over the 45 same, the latches of the upper needles passing between the edge y' and the latch-opener and being prevented by said edge from swinging upwardly too far. The guard also has an inclined front side, z' , which extends nearly to 50 the lower needle-latch opener, k' , and prevents the latches of the lower needles from being thrown upwardly by accident after passing said latch-opener, the surface z' extending from the latch-opener k' nearly to the thread-feed v' , so that the latches of the lower needles 55 cannot be thrown upwardly until they are in position to direct the thread into the hooks of their needles.

The arm s' is provided with a screw, a' , which 60 abuts against the surface of the upper cam-cylinder, and acts as an adjustable stop, determining the point to which the arm s' may be forced toward the needles by the spring t' . Said spring presses outwardly on the upper 65 end of the arm s' above its pivot, and thus forces its lower end upwardly toward the needles.

The needle-path in the lower cam-cylinder, which acts on the heels of the lower needles, is shown as developed on a plane surface in 70 Fig. 14.

The needles in advance of the latch-opener k' are raised by an incline, 2, to a horizontal groove, 3, and are then depressed by an inclined groove, 4, which carries them to the 75 lowest point required to cause the loop around each needle to raise the latch thereof, and to cause each needle to withdraw from the loop around it and to draw the thread engaged with its hook by this movement of the latch 80 downwardly through said loop, thus completing a stitch. The inclined groove 4 communicates with a groove, 5, and the latter with an upwardly-inclined groove, 6, which raises the needles after each has completed a stitch, 85 and thus elevates the latch of each needle above the loop last formed.

The incline 2 is the upper edge of a loose block or trap, d^2 , having a pin or stud, b^2 , which is free to play in a slot, c^2 , in the wall of 90 the cam-cylinder e , the block d^2 resting loosely on a block, f^2 , which forms the upper side of reversed counterparts 4', 5', and 6' of the grooves 4, 5, and 6, the lower end of the block d^2 extending across the groove 6' and preventing the needle-heels from entering said groove 95 when the cam-cylinder e is rotating in direction indicated by the dotted arrow in Fig. 14, this being the direction in which the cylinder is rotated when the machine is operating normally. A reversed duplicate, d^3 , of the block-trap d^2 is placed over the grooves 4, 5, and 6, and normally covers the upper end of the groove 6, but does not obstruct the egress of 100 the needle-heels from said groove, but is 105 raised, as shown in Fig. 14, by each needle-heel. The blocks or traps being capable of vertical movement and of assuming their groove-obstructing positions by gravitation, 110 are positive in their operation and not liable 115 to stick in any improper position.

The upper surface of the groove 3 is a block, g^2 , which is adapted, by means of slots h^2 and screws i^2 i^2 entering the cylinder e through said slots, to slide horizontally, and thus 120 form an opening at the upper side of the groove 3 at one end or the other. When the block is in the position shown in Fig. 14, the end of the groove 3 adjacent to the incline needle-heels dropping into the 2 is open, the 125 groove 3 from said incline. Should the direction of rotation of the cylinder e be reversed, the block d^3 would remain depressed, as shown in dotted lines in Fig. 14, and would therefore obstruct the upper end of the groove 6. The needle-heels would therefore ride on the upper edge of the block d^3 , and would thus be elevated to the block g^2 , which would yield, as shown in dotted lines, and allow the needle-heels to drop into the groove 3. Thereafter 130 the needles would be depressed by the groove 4' and raised by the groove 6'. The direction of rotation being again reversed, the needle-heels will pass up the block d^3 , down the groove

4, and up the groove 6, as first described. The machine is thus operated in forming the heel, the cylinder *e* being oscillated to form interrupted rows of stitches alternately from left to right, and from right to left, one or more needles being dropped at each end of the series of needles after each row is formed until the heel is sufficiently narrowed, after which one or more needles are added after each row 10 is formed until the bottom of the heel is sufficiently widened. This mode of operation is not new, however, and is not claimed by me.

When the cylinder *e* rotates continuously, as usual, the needle-heels rest on the intermediate fixed horizontal portion *j*² of the needle-path, which supports the needles at a suitable height to enable the incline or block 2 to engage and raise them, as above described. The continuity of the portion *j*² is interrupted by the angular ends of two blocks, *k*², which are vertically movable, and are positively held at any position to which they may be adjusted by set-screws *l*, passing through vertical slots in the cylinder *e*, the heads of said screws bearing on the outer surface of the cylinder. These blocks, which I term "shakers," are used to insure the proper elevation of the needles to cause their latches to pass above the loops encircling the needles in case said loops are so tightly drawn as to prevent the needles from "jumping" slightly as they emerge from the inclined groove 6. When the knitting is loose and the needles are not thus restricted, the shakers are not required and are depressed 30 below the level of the surface *j*², thus obviating wear on the needle-heels and liability of too high elevation of the needles, which would occur if the shakers were continually used.

The lower cam-cylinder is vertically movable in the space between the inclosing-shell *d* and the needle-cylinder *b*, and to its lower edge is secured an internally-grooved ring, *m*².

*n*² represents a ring with a peripheral tongue, which enters the groove in the ring *m*². The inner ring, *n*², is capable of moving vertically on the reduced lower end of the needle-cylinder, below the slotted needle-holding portion thereof, and is provided with inwardly-projecting studs *o*², which pass through vertical slots *p*² in the needle-cylinder *b*. Within the needle-cylinder is a band, *q*², held in place by lugs *r*² bearing against its lower edge, and a shoulder, *s*², bearing against its upper edge. The band *q*² is capable of rotating in the needle-cylinder *b*, and is provided with inclined slots *t*², which receive the studs *o*². When the band *q*² is rotated, the inclined slots, acting on the studs *o*², cause the ring *n*² to rise or fall, as the case may be, and thus raise or lower 55 the cam-cylinder *e* and regulate the length of the stitches. The band *q*² is rotated by means of a rock-shaft, *u*², journaled in the base *a* and provided at its outer end with an operating knob or handle, and at its inner end with an arm, *v*², which enters a slot in a block, *w*², affixed to the band *q*². (See Fig. 17, in which the band and a portion of the base are shown in an

inverted position.) The rotation of the rock-shaft causes the arm *v*² to rotate the band *q*².

*y*² represents an arm attached to the band *q*², and provided at its outer end with an indicating-finger, *z*², projecting through a slot in the base *a*, over suitable marks or graduations on the exterior of the base, whereby the extent of the vertical adjustment of the cam-cylinder is indicated.

The slotted portion of the lower needle-cylinder is enlarged at *a*³, and to said enlarged portion is attached a narrow ring, *b*³, which extends across the needle-holding slots, and is provided with a shallow internal groove, *c*³, of sufficient depth to receive and support the heels of those needles which are inoperative, as when the machine is forming the heel. When the machine is thus used, the rubber attachment is removed, and of the needles in the lower cylinder which are raised and used in the operation every alternate one is raised and supported by the engagement of its heel with the groove *c*³.

*e*³ represents a ring composed of hinged and flanged sections, which is placed upon the upper edge of the inclosing-shell *d*, and surrounds the needle-cylinder *b*. The flange of said ring projects into a recess, *f*³, in the slotted portion of the needle-cylinder above the enlargement *a*³, and prevents the needles from being entirely withdrawn from the needle-cylinder, the heels of the needles being arrested by said flange. This sectional flanged ring is shown in my application for Letters Patent filed in January, 1883; but in said application the enlargement *a*³ of the needle-cylinder and the grooved ring *b*³, attached thereto, are not shown, and the sectional ring is shown as provided with a groove to engage and support the heels of the raised needles.

The enlargement of the needle-cylinder and the grooved ring attached thereto are used as an improvement on the grooved flanged sectional ring, as shown in my former application.

The outward extension of the needle-holding slots to the grooved ring *b*³, caused by the enlargement of the cylinder, enables the slots to bear against the sides of the needle-heels from their inner to their outer ends, and thus prevent the needles from turning on their own axes, while the rigid attachment of the ring *b*³ to the cylinder enables the ring to hold the needle-heels and prevent the needles from tipping outwardly when the sectional ring is removed to enable removal or adjustment of one or more needles to be effected. It is sometimes necessary to remove the sectional ring for such purposes, so that when the sectional ring is used to hold the raised needle-heels, as in my former application, the raised needles are deprived of their support when the ring is removed, and are caused to tip by the strain exerted on their upper ends by the weighted fabric suspended from them.

The needle-path of the upper cam-cylinder, *i*, may be described as follows: Said cylinder

has a vertically-adjustable block, g^3 , having a horizontal side, 7, and two inclined sides, 8, 9, a fixed horizontal shoulder or ledge, h^3 , a vertically-adjustable block, i^3 , having a horizontal side, 10, and an inclined side, 11, a bridge, j^3 , pivoted at k^3 , a tongue, l^3 , pivoted at m^3 , a fixed inclined block, o^3 , and a short fixed block, n^3 . When the upper cam-cylinder is not in use, the adjustable blocks g^3 , i^3 are depressed, as shown in Fig. 13, so that their upper edges and the upper edge of the bridge j^3 form continuations of the horizontal ledge h^3 , a continuous horizontal support being thus afforded for the heel of the upper needles, so that the rotation of the cam-cylinder i gives no movement to said needles. The machine is thus used when it is desired to temporarily discontinue the use of the upper needles without disconnecting them with their cylinder from the machine.

When both the upper and lower needles are in use in making ribbed work, the blocks g^3 , i^3 are raised, as shown in Fig. 11. The edge 8 of the block g^3 depresses the upper needles in advance of the point where the stitches are formed sufficiently to push the latches of said needles downwardly through the loops surrounding the needles, and allow said latches to swing downwardly by their own weight. The upper needles, after being thus depressed, are raised by the fixed inclined block o^3 , immediately in advance of the fender m^3 , in time to cause their latches to pass over said fender, and are then slightly depressed by the lower edge of the small fixed block n^3 , and at the same time to draw the reversed latches upwardly into the loops around the upper needles to enable the latch-opener u' to engage with the latches and swing them upwardly, as shown in Fig. 7. The thread passes through the feed v' to both the upper and lower needles, and each upper needle-latch as it passes off from the latch-opener u' is drawn downwardly upon the thread by the strain of the fabric-loop surrounding the needle and latch, the thread being thus held between the latch and hook. After this the upper end of the tongue l^3 carries the upper needles upwardly to the upper edge of the block i^3 , thus causing each upper needle to draw a loop of thread through and release the loop last formed about it. The free end of the bridge j^3 , bearing on the block i^3 , yields to allow each needle-heel to pass up the tongue l^3 and onto the block, as shown in Fig. 11. After the block i^3 passes, the needles are supported by the horizontal ledge h^3 . The block g^3 is attached to T-plate p^3 , which is capable of sliding in guides formed in the inner surface of the upper cam-cylinder. A thumb-screw, q^3 , passing through a slot in the cam-cylinder, enters the block g^3 , and by the pressure of its head against the outer surface of the cam-cylinder holds said block positively in either of the positions shown in Figs. 11 and 13. The adjustment of the block i^3 determines the height to which the upper needles are raised in forming their loops or stitches, and thus

determines the length of each stitch. Said block is secured by means of a spring, r^3 , Fig. 5, to a segmental grooved slide, s^3 , which is fitted to slide upon a tongued ring, t^3 , Figs. 5 and 15. Said ring is capable of being raised and lowered on the outer surface of the upper needle-cylinder, j , and is provided with inwardly-projecting studs u^3 , projecting through vertical slots v^3 in the upper end of the upper needle-cylinder, j , into inclined slots w^3 in a band, y^3 , which is adapted to rotate between two shoulders on the inner surface of the needle-cylinder j , and is provided with a handle, z^3 , whereby it may be rotated. The rotation of the band y^3 causes the inclined slots to raise or lower the ring t^3 , which in turn raises or lowers the segmental slide s^3 and stitch-adjusting block i^3 . The spring r^3 connecting the block i^3 , the slide s^3 yields sufficiently to compensate for the slight difference in direction between the movements of the block and slide, the former moving diagonally on the inclined inner surface of the cam-cylinder, while the latter moves vertically.

I claim—

1. The combination of the upper needle-cylinder, the rotary upper cam-cylinder enclosing and supporting said needle-cylinder, a fixed segmental bar over the needle-cylinder provided with sliding detents engaged with the needle-cylinder, the thread-guide rotating with the needle-cylinder, and cams also rotating with the cam-cylinder, whereby each detent is displaced in advance of the thread and replaced after the thread carried by the thread-guide has passed, as set forth.

2. The combination of the stationary lower needle-cylinder, the lower cam-cylinder rotating therearound, the upper cam-cylinder, a connecting device, substantially as described, whereby the upper cam-cylinder is detachably connected to and rotated by the lower cam-cylinder, the upper needle-cylinder supported wholly by the upper cam-cylinder and entirely disconnected from the lower needle-cylinder, an independent fixed bar over the upper needle-cylinder, and devices, substantially as described, whereby the upper needle-cylinder is engaged with said bar, and thereby made stationary or prevented from rotating with the cam-cylinder supporting it, as set forth.

3. The combination of the upper needle-cylinder, the segmental bar n , having the sliding detents p , whereby the upper needle-cylinder may be held stationary, the swiveled standard supporting said bar, the locking devices for said standard, and the spring whereby said standard is raised and rotated when unlocked, as set forth.

4. The upper cam-cylinder having the arm or standard l , combined with the lower cam-cylinder having the socketed projection m , formed to engage with the lower end of said standard, and the lever e' , pivoted to the standard and bearing on the projection m , as set forth.

5. The combination, with the lower needle-cylinder and its needles and operating mechanism for the latter, of the cam-cylinder provided with a projection, the lever g' , pivoted to said projection and provided with the latch-opener h' , which enters the eyes of the needles, the shoe or fender m' , which bears against the front sides of the needles, means, substantially as described, for pressing the lever and its attachments inwardly toward the needles, and means whereby the shoe or fender may be adjusted toward or from the lever to adjust the latch-opener relatively to the eyes of the needles, as set forth. 70
- 10 6. The combination, with the lower cam-cylinder provided with a projection, the lower needle-cylinder and its needles, of the slotted arm g' , pivoted to the projection on the cam-cylinder, and provided at its upper end with the latch-opener h' , the spring l' , whereby the lever g' is pressed upwardly, and the hook p' , projecting through the slot in the arm, and the elastic metal strip on said lever engaged with said hook, as set forth. 75
- 15 7. The combination, with the upper needle-cylinder, its needles, and their operative mechanism, of the upper cam-cylinder, the arm s' , pivoted thereto, and the latch-opener secured to said arm and consisting of the diagonal finger pointed at its lower end and having the feed v' at its upper end, as set forth. 80
- 20 8. The combination, with the upper needle-cylinder, its needles, and their operating mechanism, of the upper cam-cylinder, the lever s' , pivoted thereto, the latch-opener u' , secured to the lever and composed of the diagonal finger pointed at its lower end and having the feed v' at its upper end, and the arm or guard w' , also secured to the lever, and 85
- 25 having an inclined edge, y' , which is substantially parallel with the diagonal latch-opener, as set forth. 90
- 30 9. The combination, with the upper and lower needle-cylinders, their needles and the operating mechanism for said needles, of the upper and lower cam-cylinders, the latch-opener for the lower needles, a lever pivoted to the lower cam-cylinder, supporting said latch-opener, as described, the lever s' , pivoted to the upper cam-cylinder, the latch-opener u' , formed as described and secured to said lever s' , and the arm or guard w' , also secured to the lever s' , and having the inclined surfaces y' and z' , as set forth. 95
- 35 10. The combination of the upper needle-cylinder and its needles, the upper cam-cylinder having the fixed ledge or shoulder h^3 , the adjustable three-sided block g^3 , the fixed incline o^3 , co-operating with one side of said block, the short fixed block n^3 , whereby the upper needles are depressed after being raised by the incline o^3 , the pivoted tongue l^3 , and the adjustable block i^3 , against which the tongue bears, as set forth. 100
- 40 11. The upper cam-cylinder provided with the fixed ledge or shoulder h^3 , the adjustable block g^3 , the pivoted bridge j^3 , and the adjustable block i^3 , all forming continuations of the ledge h^3 when the blocks g^3 i^3 are depressed, as set forth. 105
- 45 12. The combination of the upper needle-cylinder and its needles, the upper cam-cylinder having the externally-tongued vertically-movable ring on its outer surface, and the adjustable block i^3 on its inner surface, the segmental slide s^3 , fitted to move in the tongued ring, a spring, r^3 , connecting said slide to the adjustable block i^3 , and means, substantially as described, whereby the tongued ring may be raised and lowered, as set forth. 110
- 50 13. The combination of the lower needles, the lower needle-cylinder, and the lower cam-cylinder, provided with slots b^2 , and having the needle-path composed of the horizontal groove 3, the inclined grooves 4 5 6 4' 5' 6', and the ledge or shoulder j^2 , with the blocks f^2 , and the loose blocks or traps resting on said blocks f^2 , and on the shoulder j^2 , and normally obstructing the grooves 6 6', and provided with pins c^2 , entering said slots b^2 in the lower cam-cylinder, whereby said traps are enabled to move or yield upwardly but not laterally, and are permitted to assume their groove-obstructing positions by gravitation, as set forth. 115
- 55 14. The combination of the lower needle-cylinder and the rotating vertically-movable lower cam-cylinder having the grooved ring m^2 , attached to its lower edge, with the non-rotating vertically-movable sectional ring n^2 on the lower needle-cylinder, provided with a tongue fitting the groove of the ring m^2 , and provided with studs o^2 , the band q^2 , having inclined slots receiving said studs, and mechanism, substantially as described, whereby said band may be rotated to raise and lower the ring m^2 with the lower cam-cylinder, as set forth. 120
- 60 15. The combination of the lower cam-cylinder having the grooved ring m^2 , the lower needle-cylinder having vertical slots p^2 , the sectional ring n^2 on the exterior of the needle-cylinder, provided with a tongue fitting the grooved ring m^2 , and provided with studs o^2 , projecting inwardly through the vertical slots in the needle-cylinder, the rotary band q^2 within the needle-cylinder, having inclined slots receiving the studs o^2 , the base a , and the rock-shaft u^2 , journaled in the base, and having an arm engaged with the band q^2 , as set forth. 125
- 65 16. The combination, with the vertically-movable lower cam-cylinder, e , of the vertically-slotted needle-cylinder, the sectional tongued ring on the outside of said needle-cylinder engaged with the grooved ring of the cam-cylinder, and having studs o^2 , the rotary band q^2 within the needle-cylinder, having inclined slots receiving the studs o^2 , means, as described, whereby said band may be rotated, an indicating-finger connected with said band, the base a , provided with marks and graduations on the exterior of the base co-operating with said finger to indicate the 130

extent of the vertical adjustment of the cam-cylinder, as set forth.

17. The lower needle-cylinder having the needle-holding slots in its periphery, the peripheral enlargement a^3 , through which said slots pass, and the continuous internally-grooved ring b^3 , secured to said enlargement and crossing the slots therein, as set forth.

In testimony whereof I have signed my name to this specification, in the presence of two ~~10~~ ¹⁰ subscribing witnesses, this 17th day of December, 1884.

GEORGE A. WHITE.
